UNITED STATES PATENT OFFICE.

ANDREW O. BORG, OF RICHMOND, VIRGINIA.

BENCH-CLAMP.

1,362,222.

Specification of Letters Patent. Patented Dec. 14, 1920.

Application filed May 22, 1920. Serial No. 383,516.

To all whom it may concern:

Be it known that I, ANDREW O. BORG, a citizen of the United States, residing at Richmond, in the county of Henrico and State of Virginia, have invented certain new and useful Improvements in Bench-Clamps, of which the following is a specification, reference being had to the accompanying drawings.

10 This invention relates to an improved bench clamp and an object is to provide a clamp of this character for adjustment relatively to the bench so as to hold the work regardless of its width or thickness between 15 the clamping member and the side of the bench.

Another object is to provide a bench clamp, adjustable relatively to the bench and including a pair of jaws, one constituting 20 a holding jaw for an operating screw and the other jaw constituting a clamp proper for adjustment relatively to the screw holding jaw so as to clamp the work between the last mentioned jaw and the side 25 of the bench.

Still another object resides in a bench clamp wherein novel means is afforded for permitting the bench clamp to be quickly adjusted relatively to the side of the bench 30 so that all classes of work can be clamped between the clamp and the side of the bench, and there being an auxiliary clamping jaw adjustable relatively to the screw holding 35 jaw, in order to insure making close adjustments. For instance, the clamp may be adjusted very quickly by pulling the clamp carrying frame out from the side of the bench and positioned substantially relatively to the work, whereby the auxiliary 40 clamping jaw may be adjusted slightly to engage the work and clamp the same securely.

A further object resides in the provision of a bench clamp wherein a frame including 45 racks engageable with bars of the bench for holding the clamp in guides for guiding the frame, thereby enabling the bench clamp to be quickly adjusted by pulling the frame outwardly from the side of the bench and engaging the teeth of the racks with the bars 50 of the bench.

A still further object is to provide a bench clamp which is quickly adjustable to accommodate large and small work when 55 clamped between the auxiliary clamping jaw and the side of the bench, with means for adjusting the auxiliary clamping jaw.

While the design and construction at present illustrated and set forth is deemed preferable, it is obvious that as a result of a 60 reduction of the invention to a more practical form for commercial purposes, the invention may be susceptible to changes, and the right to these changes is claimed, provided they are comprehended within the 65 scope of what is claimed.

The invention comprises further features and combination of parts, as will be herein-after set forth, shown in the drawings and claimed.

In the drawings:

Figure 1 is a view showing the application of the improved clamp as applied to a work bench,

Fig. 2 is a cross sectional view through 75 the same showing the operating screw as engaging a socket in the auxiliary clamping jaw and showing the construction of the rack teeth of the frame; and

Fig. 3 is a detail view on the line 3—3 80 of Fig. 2.

Referring to the drawings, 1 designates a work bench, which comprises the opposite sides 2, the top 3 of the bench, and 4 denotes a guide bar connecting the sides of 85 the bench. One of the sides 2 of the bench is provided with openings 5 and 6 and extending across the lower inner part of the opening 5 is a holding bar 7 which is secured by screws 9 or the like to the side 90 of the bench. The lower outer portion of the opening 6 has a similar holding bar 8 which is secured by screws 10. These bars 7 and 8 protrude upwardly above the bottoms of the openings 5 and 6 to be engaged 95 by racks.

A frame 11 is provided, and which comprises a clamping jaw 12, the rack bars 13 which are disposed horizontally in parallelism and the brace bars 14, which extend 100 vertically and are in parallelism. The bars 14 connect the inner ends of the rack bars 13 in order to relatively brace them. The teeth 15 of the upper rack bar 13 have rounded corners 16 so that when the frame 105 11 is slightly tilted, the teeth may slide over the bar 7 when the frame is moved inwardly. The teeth 17 of the lower edge of the lower bar 13 have rounded corners 18, which permit the lower rack bar 13 to slide over the 110 bar 8 when the frame 11 is tilted in the opposite direction to permit the frame to slide inwardly. The rounded corners 16 and 18 are reversely disposed so as to per-

mit the frame 11 to move inwardly and outwardly from the work bench, it depending entirely upon the direction of tilt of the frame.

5 The vertical bars 14 are secured to the inner ends of the bars 13 as at 19 and 20 by means of a pair of pins. The pins 19 and 20 hold the bars 14 rigidly at right angles to the bars 13 so as to provide a 10 substantial frame. Passing transversely through the upper ends of the bars 14 is a journal pin 22 carrying the roller 23 which engages upon the upper face of the guide bar 4, so as to guide the frame inwardly and 15 outwardly from the bench.

The operating screw holding an abutment jaw 12 is secured to the outer ends of the bars 13 as by means of pins 24 arranged in pairs, and fixed in the upper end of the 20 holding or abutment jaw 12 is a threaded bushing or sleeve 25 through which a screw 26 engages. One end of the screw terminates in a head 27 transversely of which a hand rod 28 movably extends.

25 The opposite ends of the hand rod 28 are provided with nuts or heads 29 detachably threaded thereto so as to limit the hand rod in either one of its reciprocating movements through the head 27. Pivoted by a pin 30 to the lower bar 13 is the lower end of a clamping jaw 31 which has an opening 32 through which the bar 13 engages. The clamping jaw 31 has an additional opening 33 through which the upper bar 13 extends 35 so as to permit the clamping jaw 31 to be moved pivotally with relation to the side of the bench and with relation to the clamping jaw 12.

An expansion coil spring 34 is interposed 40 between the lower end of the jaw 12 and the lower end of the jaw 31 there being retaining lugs 35 on the adjacent faces of the lower ends of the jaws 12 and 31 in order to retain the expansion spring 34 in position.

45 The inner end of the screw 26 engages a socket 26^a in a plate 26^b which is secured in any suitable manner in one face of the clamping jaw 31. When it is desired to hold a piece of work such as indicated in dotted 50 lines in Fig. 2 between the clamping jaw 31 and the side of the bench regardless of the width or thickness of the work, the frame which includes the bars 13 may be quickly adjusted outwardly from the bench a requisite distance to receive the work. It is 55 to be noted that the teeth in the rack bars 13 are relatively large and are disposed relatively to each other so as to engage the plates 7 and 8, and owing to the size of the 60 teeth the frame cannot be adjusted so that the jaw 31 can properly engage the work to hold it in position, therefore, after placing the work between the jaw 31 and the bench it is necessary to adjust the jaw 31.

The adjustment of the jaw 31 is accomplished by turning the operating screw 26 and owing to the inner end of the screw engaging the socket the jaw 31 may be moved toward the work and clamp it securely between the bench and the jaw. The jaw 13 70 will act as an abutment together with the straight edge of the teeth 15 thereby preventing outward movement of the abutment jaw 12 relatively to the bench when the work is clamped between the jaw 31 and the bench. It is to be noted that the jaw 31 is adjustable relatively to the abutment jaw 12 and is capable of fine adjustments. A bench clamp of this character can be used for clamping wide articles such as drawers 80 and the like between the jaw 31 and the side of the bench indicated in dotted lines in Fig. 2.

When it is desired to disengage the work from the jaw 31 and the side of the bench, 85 the operating screw is rotated so as to move outwardly through the abutment jaw 12 and in this case the jaw 31 will disengage the work, owing to the action of the spring 34 which will swing the jaw 31 on its pivot 30 90 and cause the upper end of the jaw 31 to disengage.

By the provision of a clamp of this character it will be seen that the bench clamp can be adjusted very quickly relatively to 95 the bench and then the fine adjustments can be made by adjusting the jaw 31, and furthermore the face of the work can be clamped securely in position.

The invention having been set forth, what 100 is claimed as new and useful is:—

In a bench clamp, a guide bar connecting the opposite sides of the bench, one side of the bench having openings, a clamp supporting frame comprising parallel bars engaging through and having rack teeth connections with said openings to hold the frame in different adjusted positions relatively to the side of the bench, a member connecting the inner ends of said bars and being guided upon the guide bar, an abutment jaw connecting the outer ends of said bars, a movable bench clamping jaw pivoted on the lower bar of said frame and having an opening through which the upper bar of said frame passes, a spring interposed between the lower extremity of the bench clamping jaw and the abutment jaw below the pivot of the bench clamping jaw to move the upper end of the bench clamping jaw from 120 the work, and a screw, including means for rotating it, and having a socket engagement to the bench clamping jaw, to move the jaw toward and clamp the work against the side of the bench.

125 In testimony whereof I hereunto affix my signature.

ANDREW O. BORG.
